FLOOR STRIPPING MACHINE

Roy H. Stein, 3920 Zephyr St., Wheatridge, Colo.

Filed Apr. 7, 1965, Ser. No. 84,654

Term of patent 14 years

(Cl. D37—1)

FIG. 1.

FIG. 2.

FIG. 3.

FIG. 4.

I claim:

The ornamental design for a floor stripping machine, as shown and described.
